UNITED STATES PATENT OFFICE.

VERDA V. STEWART, OF WEYERS CAVE, VIRGINIA.

HAIR-BRUSH.

1,258,375.

Specification of Letters Patent.

Patented Mar. 5, 1918.

Application filed November 18, 1916. Serial No. 132,171.

To all whom it may concern:

Be it known that I, VERDA V. STEWART, a citizen of the United States, residing at Weyers Cave, in the county of Augusta and 5 State of Virginia, have invented certain new and useful Improvements in Hair-Brushes; and I do hereby declare the following to be a full, clear, and exact description of the invention, such as will enable others skilled in 10 the art to which it appertains to make and use the same.

This invention relates to an electrical hair brush and has for one of its objects the provision of a device of this character, especially adapted for straightening and 15 drying hair.

Another object of the invention is to provide a body, having an electrically heated plate therein to which are formed a plurality 20 of metallic teeth, that are heated by the plate, whereby the hair of a person may be readily dried and straightened.

A further object of the invention is the provision of a hair brush of the above stated 25 character, which shall be simple, durable and efficient, and which may be manufactured and sold at a comparatively low cost.

With these and other objects in view as will become more apparent as the description 30 proceeds, the invention consists of certain novel features of construction, combination and arrangement of parts as will be hereinafter more fully described and claimed.

35 For a complete understanding of my invention, reference will be had to the following description and accompanying drawing, in which:

Figure 1 is a side elevation of a hair brush 40 constructed in accordance with my invention.

Fig. 2 is a top plan view partly in section of the same, illustrating the resistance coils for heating the plate, and

45 Fig. 3 is a transverse sectional view taken on the line 3—3 of Fig. 2.

Referring in detail to the drawing, the numeral 1 indicates a hollow body in which is positioned a metallic plate 2 having a plurality 50 of teeth 3 formed thereon, which de-

pend through a plurality of apertures in the bottom wall of the body 1. The metallic plate is covered by insulating material 4 on which is positioned an electrical resistance coil 5 and has its ends connected to terminals 6. The resistance coil 5 is covered by insulating material 7 which co-operates with the insulating material 4 to insulate the resistance coil from the body 1 and the plate 2. A removable cover 8 is detachably secured to the body 1 whereby the insulating materials, resistance coil and plate may be removed from the body 1 when desired.

Formed upon the body 1 is a hollow handle 9 adapted to receive conductors 10 that 65 are connected to the binding posts 6 and the other ends which may be readily attached in the usual manner to an electrical source for furnishing the resistance coil with electrical current for heating the plate 2 and 70 the teeth 3, thus the hair of a person may be readily combed with the teeth 3 so as to dry and straighten the same. This brush is preferably used upon very short hair with which an electrical comb cannot be used 75 efficiently.

While I have shown and described the preferred embodiment of my invention, it will be understood that minor changes in construction, combination and arrangement 80 of parts may be made without departing from the spirit and scope of the invention as claimed.

Having thus described my invention, what I claim is:

85 A hair brush comprising a hollow body having a plurality of apertures in the bottom wall thereof, a metallic plate positioned within the body and spaced from the side walls thereof, a plurality of teeth formed upon the under face of the plate and depending through the apertures of the bottom wall of said body, insulating material overlying said plate, flanges formed upon the periphery of said insulating material 90 and extending upwardly and downwardly therefrom against the side walls of said body and forming a coil receiving space upon said insulating material, a coil located within said coil receiving space, an insulat- 100

ing material overlying said coil and coöperating with the flanges to insulate the coil from the body, a cover closing said body, means connecting the coil to an electrical source, and a hollow handle formed on said body.

In testimony whereof I affix my signature in presence of two witnesses.

VERDA V. STEWART.
